Primary Examiner — Austin Murphy

(57) **CLAIM**

I claim the ornamental design for a combined boot and glove dryer, as shown and described.

DESCRIPTION

FIG. 1 is a top perspective view of the combined boot and glove dryer;

FIG. 2 is a top view of the combined boot and glove dryer;
FIG. 3 is a bottom perspective view of the combined boot and glove dryer;

FIG. 4 is a bottom view of the combined boot and glove dryer;
FIG. 5 is a left or right end view of the combined boot and glove dryer; and,

FIG. 6 is a front or back view of the combined boot and glove dryer.
